VEHICLE DOOR WINDOW CONSTRUCTION

Harry Rainier, Los Angeles, Calif.

Application January 26, 1933, Serial No. 653,662
Renewed March 25, 1935

10 Claims. (Cl. 296—44)

This invention relates to improvements in vehicle door window constructions.

An object of the invention is to provide an improved door window wherein there is a pane which can be elevated from the pane receiving pocket conventionally provided in a vehicle door to a position over the window opening. In this construction the pane is transversely divided into upper and lower sections and specifically an object of the invention is to provide a construction for automatically causing the lower section of the pane to be swung outwardly when the upper section of the window pane approaches the upper limit of its movement. In this manner the upper section forms a closed window while the lower section can be swung outwardly to provide suitable ventilation and an opening for giving arm signals, if the window happens to be that located next to the driver's seat.

Another object of the invention is to provide a vehicle door window construction having the above mentioned characteristics, wherein the operating mechanism employed for raising and lowering the window pane causes the automatic outward swinging movement of the lower section to take place.

Another object of the invention is to provide a construction wherein the lower section is forcibly closed or swung back into alignment with the upper section of the window pane during the start of the downward movement of the upper section of the window pane. In this way the lower section will always be caused to align with the upper section before entering the pane receiving pocket.

Another object of the invention is to provide a window construction for vehicle doors wherein there is an upper section and a lower section, the lower section being pivoted for movement relatively to the upper section, and to provide a construction wherein these sections of the pane are in edge to edge relation without any binding strips or channels which detract from the appearance of the window and also have a tendency to obstruct the view therethrough.

With the foregoing and other objects in view, which will be made manifest in the following detailed description, and specifically pointed out in the appended claims, reference is had to the accompanying drawings for an illustrative embodiment of the invention, wherein:

Fig. 1 is a vertical section through the improved vehicle door, illustrating the construction embodying the invention in lowermost position.

Fig. 2 is a view similar to Figure 1, illustrating the construction in uppermost position.

Fig. 3 is a horizontal section taken substantially upon the line 3—3 upon Figure 1.

Fig. 4 is a horizontal section taken substantially upon the line 4—4 upon Figure 2.

Fig. 5 is a horizontal section taken substantially upon the line 5—5 upon Figure 2.

Fig. 6 is a view similar to Figure 2, illustrating a slightly modified form of construction.

Fig. 7 is a horizontal section taken substantially upon the line 7—7 upon Figure 6.

Fig. 8 is a vertical section taken substantially upon the line 8—8 upon Figure 7, the lower section of the pane being shown in aligned position with the upper section preparatory to entering the pane receiving pocket.

Referring to the accompanying drawings, wherein similar reference characters designate similar parts throughout, the door in which the improved construction is illustrated as having been mounted consists of top and bottom rails 10 and 11, connected by upright stiles 12. These stiles are also connected by a sill 13. Inner and outer walls 14 and 15, which may be provided by sheet metal, connect the stiles 12 from sill 13 to bottom rail 11, forming a pane receiving pocket 16 which is beneath the window opening 17 between the sill 13 and top rail 10. On the inner faces of the stiles and within the pane receiving pocket 16 there are provided grooved guides 18 for a frame 19 for the window pane. This frame 19 has channeled sides 20 and a bottom 21. The channeled portions of the sides extend downwardly from the top of the upper section 22 of the window pane only a distance equal to the height of the upper section. Below the bottom 21 edge of the upper section 22 the sides of the frame are flat and unchanneled. The guides 18, which guide the frame, terminate opposite sill 13 and thereabove a suitable channeled weather strip 23 is mounted on each stile. This weather strip may be of heavy felt or any conventional weather stripping used to embrace the sides of vehicle window panes.

Any conventional mechanism may be employed for raising and lowering the frame 19. The apparatus shown consists of an endless chain 24 trained over upper and lower sprockets 25 and 26. The upper sprocket can be rotated by a crank 27 and a lifter 28 connects the bottom 21 of the frame to the chain. It is obvious that upon rotation of crank 27 the frame 19 and the upper section of the window pane will be elevated. Usually the friction between the weather stripping 23 and the sides of the frame is sufficient to hold the frame and upper section of the window pane 55

in any adjusted position so that by releasing the crank 27 the window pane will be held in any intermediate position between the extreme positions shown.

- 5 Beneath the bottom edge of the upper section of window pane 22 there is a lower section 29. This section of the window pane is in edge to edge relationship with the upper section 22. Its sides are embraced in channels 30, which may be formed of sheet metal, each channel carrying a projecting pin 31 which fits in an aperture in the frame 19 immediately beneath the bottom edge of upper section 22. In this manner the lower section 29 is pivoted for rotation about an axis very close to its top edge. The channels 30 carry side shields 32, these being preferably in the form of a segment of a circle, and these side shields carry bifurcated extensions 33, the entrances to which are preferably widened.
- 10 These side shields are movable in vertical passages 34, provided by sheet metal 35 surrounding each stile. A pin or nail 36 is driven into each stile so as to be located in the path of the bifurcated extension on each side shield. The
- 15 groove 37, which may be lined with weather stripping 38 and which is formed in the under side of top rail 10, is preferably made a little deeper than the groove formed in the conventional vehicle door window to receive the upper
- 20 end of the window pane.
- 25
- 30

The operation and advantages of the improved construction are as follows. It will be noted that the two sections of the window pane may assume a position entirely concealed within pocket 16 as shown in Figure 1 wherein the window opening 17 is fully opened. If it is desired to have a closed window, the operator merely rotates crank 21, elevating the frame and both sections of the pane. The lower section 29 remains in alignment with the upper section until the upper edge of the upper section 22 has entered groove 37. In this position, wherein the top of upper section 22 is entered the groove but is still disposed a short distance from the very top of the groove, lower section 29 remains in alignment with upper section 22 forming a completely closed window. If the operator desires a small amount of ventilation from immediately above the sill 13, he continues rotation of crank 27 only slightly. This elevates both sections of the pane a very short distance and pin 36, having entered the bifurcated extension 33, causes section 29 to be swung outwardly. Continued elevation of the frame by means of crank 27 causes the lower section to be swung out still farther until the upper section 22 has reached the very top of groove 37. Under these conditions maximum ventilation is provided through the opening opened by lower section 29. Also a suitable opening is provided for arm signals. The frictional engagement between the frame and the weather stripping 23 is sufficient to hold the upper section 22 in any adjusted position and consequently it is possible to so adjust the construction as to cause lower section 29 to give any desired opening and to remain in such adjusted position. On reversely rotating crank 27, the initial downward movement of frame 19 causes lower section 29 to be automatically and positively returned to a position in alignment with upper section 22 before it enters pocket 16. It will, of course, be appreciated that it is not necessary to lower the pane entirely from the position shown in Figure 2 and, if desired, reduced ventilation may be obtained by only partially

lowering the upper section 22 forming a suitable opening between its top edge and top rail 10. In this way the operator may obtain ventilation from either the top or bottom of the window opening 17 if desired.

In the modification illustrated in Figures 6, 7 and 8, the door is provided with the top rail 40, bottom rail 41, sill 42 and stiles 43. In this form of construction the window pane may be disposed centrally of the stiles and rails. The pocket 44 is formed as before, in which there are guides 45 for the frame 46 having the lifter 47 attached to the endless chain 48 passing over the sprockets 49 and 50. The upper sprocket is rotated by crank 51. The upper section 52 is 15 stationarily mounted in the frame while the lower section 53 carrying the side wings 54 is pivoted adjacent its top edge on a pin 55. This pin has an angular extension or crank 56, the extreme end of which is disposed in a vertical 20 groove 57 formed in each stile. The upper end of this groove is angular, or inclined, as indicated at 58, and is preferably protected by means of a face plate 59.

During upward movement of the frame 46 25 from the pocket 44, the end of pin 55 merely slides in the vertical groove in each stile, thus maintaining the lower section 53 in perfect alignment with upper section 52 of the pin. On approaching the upper end of the movement of the 30 upper section 52 the end of the pin 55 enters the angular portion of the slot, thus forcibly and automatically swinging the lower section 53 outwardly into the position shown in Figure 6. Conversely on downward movement of the frame 35 35 the lower section 53 is first automatically and positively returned to a position in alignment with upper section 52 and then enters the pocket.

The purpose of the side shields in both forms of constructions is to prevent a sweeping draft 40 through the opening formed by the outward swinging of the lower section. In both constructions it will be appreciated that the lower section 53 is automatically and forcibly caused to swing outwardly only when the upper section reaches 45 the extreme upper end of its movement. It is possible to have the upper section partially enter its respective groove with the lower section remaining in alignment therewith. This forms a completely closed window. A slight continued 50 upward movement produces an outward swinging of the lower section. It is obvious that the lower section can be caused to assume any intermediate position by proper manipulation of the same operating crank which raises and lowers the window pane.

In both types of constructions it will be noted that the lower section of the pane swings out from adjacent its top edge and that the top edge of the lower section remains substantially 60 in contact or very close to the bottom edge of the upper section. Whether the window pane is open or closed, that is regardless of whether the lower section is swung outwardly or in alignment with the upper section, the arrangement is such 65 as to effectively prevent rain or snow entering the vehicle. It is possible to keep the window normally closed and when it is desired to give an arm signal it may be quickly opened by a simple manipulation of the crank of the elevating 70 mechanism. Thereafter it may be easily and quickly closed by a reverse operation of the same crank.

Various changes may be made in the details of construction without departing from the spirit 75

or scope of the invention as defined by the appended claims.

I claim:

1. A vehicle window having means for elevating and lowering the pane, said pane being transversely divided into upper and lower sections, means for guiding the upper section during its opening and closing movement so as to maintain it in substantially the same plane throughout its movement, and means for causing the lower section to be swung outwardly automatically when the upper section approaches the extreme end of its upward movement.
2. A vehicle window having its pane transversely divided into upper and lower sections, means for raising and lowering said sections, means for guiding the upper section to maintain it in substantially the same plane throughout its movement, and means for automatically causing the lower section to be swung outwardly when the upper section approaches the extreme end of its upward movement.
3. A vehicle window having its pane transversely divided into upper and lower sections, means for raising and lowering said sections, means for guiding the upper section to maintain it in substantially the same plane throughout its movement, and means for automatically causing the lower section to be swung outwardly when the upper section approaches the extreme end of its upward movement, said means serving to cause the lower section to be automatically swung into alignment with the upper section at the beginning of the downward movement of the upper section.
4. A vehicle window having its pane transversely divided into upper and lower sections, a guided frame for the upper section, means for guiding the frame to keep it and the upper section in substantially the same plane throughout its movement, the lower section being pivoted upon the frame, means for raising and lowering said frame, a stationary part adjacent the path of the frame, and means carried by the lower section engageable with the stationary part for causing the lower section to be automatically swung outward when the upper section approaches the end of its upward movement.
5. A vehicle window having its pane transversely divided into upper and lower sections, a guided frame for the upper section, means for guiding the frame to keep it and the upper section in substantially the same plane throughout its movement, the lower section being pivoted upon the frame, means for raising and lowering said frame, a stationary part adjacent the path of the frame, and means carried by the lower section engageable with the stationary part for causing the lower section to be automatically swung outward when the upper section approaches the end of its upward movement, said means serving to forcibly return the lower section into a position in alignment with the upper section at the beginning of the downward movement of the upper section.
6. A vehicle window having its pane transversely divided into upper and lower sections, a guided frame for the upper section, means for guiding the frame to keep it and the upper section in substantially the same plane throughout its movement, the lower section being pivoted upon the frame, means for raising and lowering said frame, a stationary part adjacent the path of the frame, and means carried by the lower section engageable with the stationary part for causing the lower section to be automatically swung outward when the upper section approaches the end of its upward movement, said means serving to forcibly return the lower section into a position in alignment with the upper section at the beginning of the downward movement of the upper section.
7. A vehicle window having its pane transversely divided into upper and lower sections, a guided frame for the upper section, means for guiding the frame to keep it and the upper section in substantially the same plane throughout its movement, the lower section being pivoted upon the frame, said pivot being located at the top edge of the lower section, means for raising and lowering said frame, a stationary part adjacent the path of the frame, and means carried by the lower section engageable with the stationary part for causing the lower section to be automatically swung outward when the upper section approaches the end of its upward movement.
8. A vehicle window having its pane divided into upper and lower sections, a frame receiving the side edges of the upper section, channels receiving the side edges of the lower section, said channels carrying pivots which pivot on the frame for the upper section, the sections being arranged in edge to edge relationship, and side shields carried by the channels adapted to close the ends of the opening produced by the lower section when the lower section is swung outwardly.
9. A vehicle window having its pane divided into upper and lower sections, a frame receiving the side edges of the upper section, channels receiving the side edges of the lower section, said channels carrying pivots which pivot on the frame for the upper section, the sections being arranged in edge to edge relationship, side shields carried by the channels adapted to close the ends of the opening produced by the lower section when the lower section is swung outwardly, said side shields carrying means adapted to engage a stationary part when the upper section approaches its uppermost position to cause the lower section to be automatically swung outwardly, and a stationary part disposed in the path of the last mentioned means engageable thereby.
10. A vehicle window having its pane divided into upper and lower sections, a frame receiving the side edges of the upper section, channels receiving the side edges of the lower section, said channels carrying pivots which pivot on the frame for the upper section, side shields carried by the channels adapted to close the ends of the opening produced by the lower section when the lower section is swung outwardly, and means providing a pocket adapted to receive said frame, channels and sections; there being an opening in the top of the pocket permitting said side shields to pass therethrough.

HARRY RAINER.
